ELECTRICAL TRANSFORMER

John W. Albright, Pittsfield, and Ernest E. Bianco, North Adams, Mass., assignors to General Electric Company, a corporation of New York

Filed Nov. 12, 1959, Ser. No. 58,304

Term of patent 14 years

(Cl. D26—15)

Fig. 1 is a perspective view of an electrical transformer, showing our new design;

Fig. 2 is an opposite end elevational view; and
Fig. 3 is a rear elevational view thereof.

We claim:

The ornamental design for an electrical transformer, as shown.
